UNITED STATES PATENT OFFICE.

BENJAMIN LIPPER, OF PHILADELPHIA, PENNSYLVANIA, ASSIGNOR TO AUGUSTUS A. LAZARUS, ISAAC A. SCHWARZ, AND BENJAMIN LIPPER, ALL OF SAME PLACE.

DESIGN FOR DRESS-TRIMMING.

SPECIFICATION forming part of Design No. 21,264, dated December 22, 1891.

Application filed November 30, 1891. Serial No. 413,596. Term of patent 3½ years.

To all whom it may concern:

Be it known that I, BENJAMIN LIPPER, a citizen of the United States, and a resident of Philadelphia, Pennsylvania, have invented a 5 Design for Dress-Trimming, of which the following is a specification.

My design is fully shown in the accompanying drawing, which represents a face view of a small piece of the trimming.

10 The design comprises the central band or tape *a*, narrow bands *b*, close to the edges of said tape, other narrow bands *d*, some distance beyond the bands *b*, fan-like figures *f*, constituting the border or edging of the fabric, 15 and a cord which lies on the face of the band or tape *a* and forms inwardly-projecting loops *i*, first at one edge and then at the opposite

edge of the said band or tape, these loops being connected by reversely-inclined crossing-cords *m*; the essential features of the design 20 being the central band or tape with its figuring face-cord and the fan-like figures forming the border or edging of the trimming.

I claim—

The design for a dress-trimming, substantially as described, and as shown in the accompanying drawing.

In testimony whereof I have signed my name to this specification in the presence of two subscribing witnesses.

BENJAMIN LIPPER.
